UNITED STATES PATENT OFFICE.

RICHARD HENRY ROBERTS, OF HENDERSON, AUCKLAND, NEW ZEALAND, ASSIGNOR
TO PERCY NICHOL KINGSWELL, OF ONE TREE HILL, AUCKLAND, NEW ZEALAND,
TRUSTEE FOR ANGLE BRACE COLLAPSIBLE BOX SYNDICATE.

COLLAPSIBLE BOX, CASE, OR CRATE.

1,347,230.

Specification of Letters Patent.

Patented July 20, 1920.

Application filed September 24, 1918. Serial No. 255,503.

To all whom it may concern:

Be it known that I, RICHARD HENRY ROBERTS, a citizen of the Dominion of New Zealand, and residing at "Farmley Tyas", Te 5 Atatu Road, Henderson, Auckland, in the Provincial District of Auckland, in the Dominion of New Zealand, have invented certain new and useful Improvements in Collapsible Boxes, Cases, or Crates, of which 10 the following is a specification.

This invention comprises braces pivoted to the lid and bottom or ends of a collapsible box or the like, so that when the box is assembled the braces extend diagonally 15 across the corners of the sides and around the ends, and when the lid, sides, ends and bottom of the box are folded the same are securely held together by the said braces in a package of minimum size.

20 The invention also comprises improvements in the details of construction and arrangement of parts which will be hereinafter described.

In the drawings herewith, Figure 1, is 25 a perspective view, Fig. 2, a side elevation, Fig. 3 an end elevation, Fig. 4, a cross sectional elevation, and Fig. 5 a sectional plan of a box embodying the invention, Fig. 6, is a side elevation showing the box partly 30 folded, Fig. 7, is a side elevation, and Fig. 8, an end elevation of the box folded, Fig. 9, is a cross sectional elevation of the box, Fig. 10, is a perspective view of a fastener and Fig. 11, is a perspective view of a 35 modified form of fastener, Fig. 12, is a sectional elevation of a detail of construction.

The braces 20 are pivoted to the bottom 21, and when the box is assembled the said 40 braces extend diagonally across the lower corners of the sides 22 and 23 and around the ends 24 and 25 of the box.

The braces 26 are pivoted to the lid 27 and extend diagonally across the upper corners of the said sides and around the said 45 ends.

The braces 20 are adapted to be retained by plates 29 in grooves 28 formed across the ends 24 and 25.

The braces 26 are adapted to be retained 50 in grooves 30 by the upper part of the plates 29, which are adapted to spring outward to allow the braces to be passed into the grooves 30.

Fig. 10 shows an ordinary turn button

31 for holding the braces in their grooves, 55 and Fig. 11 shows a plate 32 slidable on a pin 33 for the same purpose. The ends 24 and 25 abut against the ends of the sides 22 and 23 and prevent the said ends from falling inward.

60 Other suitable means for holding the braces in position may be used.

The braces may be pivoted by bending their ends 34 at a right angle and inserting the said end in holes made in the lid 65 bottom or ends as shown in Fig. 9, or the braces may have ends 35 held in grooves 36 formed in battens 37 secured to the bottom lid and ends, the terminations 38 of the ends meeting at the central part of the bottom, lid or ends of the box and being bent upward into a slot 39, whereby the same are retained, or the braces may be made endless and be retained by the said grooves 36. The ends 24 and 25 have saw cuts 40 which 70 when the parts of the box are assembled engage metal strips 42 fixed to the bottom 21, or the said ends may have tongues 44 formed along their bottom edges, the said tongues being engaged by grooves or slots 75 45 formed in the bottom 23, see Fig. 12.

To fold the parts of the case together the braces 26 are released from the grooves 30, the sides 22 and 23 are removed by drawing the same upward, and the end 24 is 80 raised pivoting on braces 20 and turned inward as shown by dotted lines in Fig. 2, the end 25 is similarly raised and turned inward, the sides 22 and 23 are laid upon the bottom 21, and the end 25 is passed below the end 24 and laid upon the said sides 85 as shown in Fig. 6.

The end 24 is then laid upon the said sides, the lid 27 is laid upon the said ends, and the braces 26 are made to engage 90 grooves 43 formed across the bottom 21, all as shown in Figs. 7 and 8.

The invention has been described herein as applied to a box, but the same may with equal facility be applied to cases or crates 100 for carrying any articles and produce where a foldable box may be required.

The box is quite rigid even after the lid 27 has been removed, so that there is no difficulty in packing the same with produce 105 or articles.

In the drawings a single brace is shown at each end of the lid and bottom but extra

braces may be used as shown by dotted lines in Fig. 1.

What I do claim and desire to secure by Letters Patent of the United States 5 is:—

1. A collapsible box having a bottom, detachable sides and ends, a removable cover, lower pivoted braces extending from the bottom diagonally across the sides and 10 horizontally across the ends, upper diagonal braces pivoted to the cover and passing diagonally across the sides and horizontally across the ends when the box is erected, means on the box ends for retaining said 15 upper braces when the box is erected and means on the bottom for engaging the upper braces and holding the parts in the collapsed position.
2. A collapsible box having a bottom, 20 movable ends mounted on the bottom, strips on said bottom for engaging saw-cuts in the said ends, removable sides mounted between the ends, braces pivoted to the bottom and extending diagonally across the 25 sides and horizontally across the ends, grooves in the ends for engaging said braces, upper diagonal braces pivoted to the cover and passing diagonally across the sides and horizontally across the ends when 30 the box is erected, grooves and retaining means on the box ends for retaining the said upper braces when the box is erected and means on the bottom for engaging the upper braces and holding the parts of the box 35 together when in the collapsed position.
3. A collapsible box having a bottom, removable ends mounted on the bottom, strips on said bottom for engaging saw-cuts in the said ends, side slots in the said 40 ends, removable sides engaging said slots,

braces pivoted to the bottom and extending diagonally across the sides and horizontally across the ends when the box is erected, grooves in the ends for engaging said braces, diagonal upper braces pivoted to 45 the sides of the cover and extending diagonally across the sides and horizontally across the ends when the box is erected, retaining devices on the box ends for engaging said upper braces, and means on the 50 box bottom for engaging the upper braces and holding the parts together when in the collapsed position.

4. A collapsible box having collapsible sides and ends, a flat bottom, diagonal 55 braces pivoted to the bottom, a cover, diagonal braces pivoted to the cover, retaining devices on the box ends for engaging all the said braces when the box is erected and means on the underside of the box bottom 60 for engaging the latter braces when the box is collapsed.

5. A collapsible box having collapsible sides and ends, a flat bottom, diagonal braces pivoted to the bottom, a cover, diagonal 65 braces pivoted to the sides of the cover and adapted to encircle one edge of the erected box and to encircle the collapsed parts and hold same together and means on the ends and bottom for engaging the said 70 braces when the box is erected and when it is collapsed.

In testimony whereof I have signed my name to this specification in the presence of two witnesses.

RICHARD HENRY ROBERTS.
